UNITED STATES PATENT OFFICE.

LIONEL NORMAN, OF WINCHESTER, MASSACHUSETTS.

MACHINE FOR MAKING PAPER VESSELS.

1,158,544.

Specification of Letters Patent. Patented Nov. 2, 1915.

Application filed February 14, 1913. Serial No. 748,338.

To all whom it may concern:

Be it known that I, LIONEL NORMAN, a citizen of the United States, residing at Winchester, in the county of Middlesex and State of Massachusetts, have invented certain new and useful Improvements in Machines for Making Paper Vessels; and I do hereby declare the following to be a full, clear, and exact description of the invention, such as will enable others skilled in the art to which it appertains to make and use the same.

The present invention relates to machines for making paper vessels and is designed particularly for use in the manufacture of paper vessels which comprise inner and outer walls, a flanged bottom inserted between the inner and outer walls, and a sealed air chamber between the walls.

The object of the present invention is to provide a simple and efficient machine for pressing together the upper and lower edges of the inner and outer walls to seal the walls at their upper and lower edges while leaving an air chamber between these points.

With this object in view a feature of the present invention contemplates the provision in a machine for making paper vessels of a holder to receive and support the outer wall and inserted flanged bottom of a vessel and an expanding plunger coöperating with the holder to force the inner wall of the vessel into engagement with the flange of the bottom and the upper edge of the outer wall. Broadly considered, the plunger may be actuated in any suitable manner to press the inner wall into engagement with the flange of the bottom and upper edge of the outer wall, but, owing to the increased thickness of the paper at the bottom of the vessel, it is preferred to actuate the plunger to exert a greater degree of outward pressure against the lower edge of the inner wall to force it into engagement with the flange of the bottom than against the upper edge of the outer wall, and this manner of actuating the plunger forms an additional feature of the invention.

This machine in addition to the features of invention above referred to also embodies certain novel constructions and arrangements of parts hereinafter described and claimed, the advantages of which will be obvious to those skilled in the art from the following description.

The several features of the present inven-

tion will be clearly understood from an inspection of the accompanying drawings, in which—

Figure 1 is a vertical section of that portion of a machine for making paper vessels showing the best form of the invention at present known to the inventor; Fig. 2 is a sectional plan view on the line 2—2 Fig. 1; Fig. 3 is a sectional plan view of the plunger on the line 3—3 Fig. 1; and Fig. 4 is a vertical section on a smaller scale of the two-walled vessel which the machine is particularly adapted to make.

The device illustrated in the drawings is provided with a holder to receive and support the outer wall and inserted flanged bottom of a paper vessel, an expanding plunger coöperating with the holder to force the upper edge of the inner wall of the vessel into engagement with the upper edge of the outer wall, and the lower edge of the inner wall into engagement with the flange of the bottom and the lower edge of the outer wall while leaving a sealed air chamber between the inner and outer walls, an actuator for expanding the plunger, and a hoop acting to force the upper edge of the inner wall flush with the upper edge of the outer wall when the plunger is depressed into the holder, and to strip the vessel from the plunger as the plunger is raised from the holder.

The holder T is provided with a side wall 1 tapering from top to bottom to receive and support the outer wall 2 of a paper vessel, and with a bottom 3 to support the inserted flanged bottom 4 of the vessel.

The plunger consists of a circular base, four segments mounted to slide radially of the base, a former section pivoted to each segment, and a pressure bar secured to each former section. The base M of the plunger is a circular plate and supports four segments E, F, G and H slidably connected to the base by means of screws o , o^2 , o^1 , and o^3 , the shanks of which are guided in radial slots m^3 , m^{11} , m^{10} and m^{12} in the base plate M. The segments are normally maintained collapsed with the apices of the segments arranged at a common point and are expanded to the circumference of the inserted flanged bottom of the vessel.

The segments carry former sections A, B, C and D pivoted respectively between lugs y , y^1 , y^2 , and y^3 , on the segments E, F, G, and H. The former sections are normally

- maintained collapsed with their adjacent vertical edges abutting and are swung about their pivoted connections with the segments as the segments are moved outwardly to exert outward pressure on the upper and lower edges of the inner wall of the vessel against the upper edge of the outer wall and the flange of the bottom to seal the outer and inner walls at their upper and lower edges
- 16 while leaving an air chamber between these points.
- The mechanism for sliding the segments E, F, G and H on the base plate M, and swinging the former sections A, B, C and D about their pivotal connection with the segments, comprises a series of pressure bars N, N¹, N², and N³ secured respectively to the former sections A, B, C and D, and an actuator carrying a series of rolls arranged to engage the series of pressure bars. The bars N, N¹, N² and N³ are respectively provided with a series of upper inclined surfaces n, n¹, and a series of lower inclined surfaces m¹⁶, m¹⁸, m¹⁷ and m¹⁹. In order to seal the inner and outer walls of the vessel at their upper and lower edges while leaving an air chamber between these points, the upper series of inclined surfaces are arranged, when the plunger is in operative position, opposite the upper edges of the inner and outer walls and the lower inclined surfaces are arranged opposite the lower edges of the inner and outer walls and the flange of the bottom. The actuator for expanding the plunger comprises a spider J with an upper series of radiating arms j, j¹, j², and j³ carrying a series of rolls m, m¹, m² and m³ which are arranged to engage respectively the upper series of inclined surfaces n, n¹, n², and n³. A second series of arms j⁴, j⁵, radiate from the spider J and carry a second series of rolls m⁴, m⁵, arranged to engage respectively the series of lower inclined surfaces m¹⁶, m¹⁸, m¹⁷, and m¹⁹. In order that the actuator and plunger may be maintained in definite relation to insure the proper engagement of the rolls and inclined surfaces, the spider J is provided with a pair of lugs j⁶ which embrace the opposite sides of the pressure bar N². The plunger is supported from the spider by a coil spring k, one end of which is suitably secured to the bottom of the spider J and the other end of which is suitably secured to the top of the plate M.
- 55 Owing to the increase in the thickness at the bottom of the vessel where the flange of the inserted bottom is interposed between the lower edges of the inner and outer walls, it is necessary to mold the lower edge of the inner wall over the flange of the inserted bottom in order that the vessel may be properly sealed at that point. For that reason greater outward pressure is required to seal the bottom of the vessel than is required to seal the top of the vessel. To obtain a

greater pressure at the bottom of the vessel than at the top the lower series of inclined surfaces are constructed with a steeper pitch than the pitch of the inclined surfaces in the upper series, the construction being such that when the actuator is reciprocated to expand the former sections the lower inclined surfaces offer greater resistance to the expanding movement of the lower series of rolls than the resistance offered by the upper series of inclined surfaces to the movement of the upper series of rolls with the result that the former sections are pressed outwardly more at the bottom than at the top.

The spider is secured to a connecting rod K mounted to be reciprocated by a hub P forming part of the machine, in which the present invention is designed for use. In order that the position of the spider may be adjusted on the rod the spider is threaded on a sleeve L which is loosely mounted on the rod below the hub P. The sleeve is provided with a series of sockets arranged for engagement with a tool by which the sleeve may be turned to adjust the spider vertically on the connecting rod while it is held from rotation by the lugs j⁶ co-operating with the pressure bar N². The adjusted position of the spider is maintained by a screw x, and a lock-nut l. The spider is connected with each of the former sections by springs w which tend to swing the sections inward about the pivotal connection with the segments.

In order that the upper edge of the inner wall of the vessel may be forced flush with the upper edge of the outer wall when the plunger is depressed into the holder, and the formed vessel stripped from the plunger as the plunger is raised from the holder, the device illustrated in the drawings is provided with a sectional hoop arranged closely about the former sections A, B, C and D. The hoop V is made in four sections corresponding to the former sections A, B, C and D, and each of the hoop sections is slidably connected by a rod R to a plate Q clamped to the hub P by a nut S on the connecting rod K. The top of each section supports a spring r which is coiled around the rod R and bears against the bottom of the plate Q for a purpose which will presently be described. The hoop sections are arranged to expand with the former sections, and co-operate with the springs w to collapse the former sections when the expanding pressure is released. To this end each of the rods R is connected by a spring r⁵ with a ring r⁶ arranged loosely around the sleeve L. As the inner faces of the sections of the hoop are held pressed against the former sections by the springs r⁵, the inner wall of the vessel is prevented from getting in between the hoop and the former sections. The bottom of the sectional hoop is thus constrained

to act as an abutment to engage the inner wall of the vessel and force the upper edge of the inner wall flush with the upper edge of the outer wall as the plunger is depressed 5 into the holder. The downward movement of the sectional hoop is limited by the top of the holder T so that during the continued actuation of the connecting rod K to expand the plunger the plate Q slides downward on 10 the rods R and thus places the springs r under tension. Upon the reverse movement of the connecting rod K to raise the plunger out of the holder the stored power of the springs r continue to press down upon the 15 formed vessel and strip it from the plunger. The hoop is again elevated when the plate Q engages the collars r^1 on the ends of the rods R. By limiting the downward movement of the hoop in the manner described 20 excessive pressure tending to crumple the walls of the vessel is prevented.

In the operation of the device illustrated in the drawings the outer wall 1 and flanged bottom 2 of the vessel, either before or after 25 being assembled, are placed in the holder T, and the inner wall 3 of the vessel is placed in the holder T, inside of the outer wall 1 and flanged bottom 2. Glue or some other adhesive is first placed, before inserting the 30 parts in the holder, on the inner and outer sides of the flange on the bottom 2 and also on the upper inside edge of the outer wall 1, and on the lower edge opposite the flange of both the inner and outer walls respectively 35 so as to cause the proper adhesion of the parts when the operation is concluded. While the parts are being assembled in the manner described, the plunger is elevated out of the holder. The plunger is now 40 moved downward into the holder, and during this downward movement the upper edge of the inner wall is forced flush with the upper edge of the outer wall by the hoop V. The series of rolls on the spider then roll 45 over the series of inclined surfaces on the pressure bars secured to the former sections and the former sections are moved outwardly to force the inner wall into place against the outer wall at the upper edges of 50 the inner and outer walls and mold the lower edge of the inner wall over the flange of the inserted bottom, and thus cause adhesion of the parts while leaving a sealed air-chamber between the inner and outer 55 walls. When the vessel is formed the connecting rod K is actuated in a reverse direction to raise the plunger out of the holder. The plunger is prevented from immediately following the actuator by the spring k which was compressed during the expanding movement of the plunger, and now serves to maintain the plunger in its expanded position in the holder until the rolls ride off the series of pressure bars carried by the former sections. At that time the plunger is collapsed

through the action of the spring w, and of the hoop which closes in on the former sections of the plunger while holding the formed vessel from moving with the plunger as it is collapsed. The plunger now moves 70 vertically with the connecting rod K. The hoop is also elevated when the plate Q engages the collars r^1 on the rods R. The formed vessel is then removed and the parts for another vessel assembled in position in 75 the holder.

The nature and scope of the present invention having been indicated and a machine embodying the several features of the invention in the best form at present known 80 to the inventor having been specifically described, what is claimed is:—

1. A machine for making paper vessels which comprise inner and outer walls, an inserted flanged bottom and a sealed air 85 chamber between the walls, having, in combination, a holder to receive the outer wall and inserted flanged bottom of the vessel an expanding plunger, and means for expanding the upper and lower portions of the 90 plunger different amounts to exert a different degree of pressure at the lower edges of the inner and outer walls than at the upper edges of the inner and outer walls to seal the walls at their upper and lower edges 95 while leaving an air chamber between these points, substantially as described.

2. A machine for making vessels, having, in combination, a holder to receive the vessel, an expanding plunger coöperating with 100 the holder to form the vessel, and means for expanding different portions of the plunger different amounts to cause the plunger to exert different degrees of pressure at different portions of the vessel, substantially as described. 105

3. A machine for making paper vessels which comprise inner and outer walls, having, in combination, a holder to receive the inner and outer walls, an expanding plunger 110 coöperating with the holder to seal the upper and lower edges of the inner and outer walls while leaving a sealed air chamber between the walls, and a hoop carried by the plunger constructed and arranged to strip the formed vessel from the plunger, substantially 115 as described.

4. A machine for making paper vessels, having in combination a holder to receive 120 the vessel, an expanding plunger coöperating with the holder to form the vessel, and a hoop arranged to expand with the plunger and to collapse the plunger when the expanding pressure is relieved, substantially as described. 125

5. A machine for making paper vessels, having, in combination, a plunger provided with a plurality of forming sections having a series of pressure bars secured thereto, and an actuator provided with a series of rolls 130

- arranged to engage the series of bars and exert outward pressure on the sections to form the vessel, substantially as described.
6. A machine for making paper vessels, having, in combination, a plunger provided with a plurality of forming sections each section being provided with a pressure bar having dissimilar inclined surfaces, and an actuator provided with a series of rolls arranged to engage the dissimilar inclined surfaces on the bars, substantially as described.
7. A machine for making paper vessels, having, in combination, a holder, and a plunger coöperating with the holder to form the vessel, comprising a base, a series of expanding segments carried by the base, and a series of formers pivotally mounted on the segments to have a bodily movement with the segments and an independent pivotal movement, substantially as described.
8. A machine for making paper vessels, having, in combination, a holder to receive the vessel, and a plunger coöperating with the holder to form the vessel, comprising a base, a series of segments carried by the base, a series of formers pivoted to the segments, and a series of pressure bars secured to the formers, substantially as described.
9. A machine for making paper vessels, having, in combination, a holder to receive the vessel, a plunger coöperating with the holder to form the vessel, a ring surrounding the plunger, and means for storing power on the ring to cause the ring to maintain pressure upon the formed vessel and strip the vessel from the plunger, substantially as described.
10. A machine for making paper vessels, having, in combination, a holder to receive the vessel, a sectional plunger coöperating with the holder to form the vessel, a hoop made in sections corresponding to the sections of the plunger arranged about the plunger, means tending to close the hoop on the plunger, and means for storing power on the hoop to maintain pressure on the formed vessel and strip the vessel from the plunger, substantially as described.
11. A machine for making paper vessels, having, in combination, a holder to receive the vessel, a sectional plunger coöperating with the holder to form the vessel, a hoop made in sections corresponding to the sections of the plunger arranged about the plunger, a vertical rod carried by each section of the hoop, a plate sliding on the rods, springs supported by the sections of the hoop coiled about the rods and bearing against the plate, and means for causing the plate to tension the springs to maintain pressure on the formed vessel and strip the vessel from the plunger, substantially as described.
